US0D1040238S

(12) **United States Design Patent** (10) Patent No.: **US D1,040,238 S**
(45) Date of Patent: ** Aug. 27, 2024

(54) **GAMING MACHINE**

(71) Applicant: **Aristocrat Technologies Australia PTY Limited**, North Ryde (AU)

(72) Inventors: **Bruce Urban**, Las Vegas, NV (US);
James Stair, Las Vegas, NV (US);
William Lamb, Eagleville, TN (US);
Dominic DeMarco, Round Rock, TX (US);
Ariel Turgel, San Francisco, CA (US);
Dan Harden, Palo Alto, CA (US)

(73) Assignee: **Aristocrat Technologies Australia Pty Limited**, North Ryde (AU)

(**) Term: **15 Years**

(21) Appl. No.: **29/760,224**

(22) Filed: **Nov. 30, 2020**

Related U.S. Application Data

(63) Continuation of application No. 29/749,672, filed on Sep. 8, 2020, which is a continuation of application No. 29/723,448, filed on Feb. 6, 2020, now Pat. No. Des. 898,128, which is a continuation of application No. 29/680,438, filed on Feb. 15, 2019, now Pat. No. Des. 875,838, which is a continuation of application No. 29/616,284, filed on Sep. 5, 2017, now Pat. No. Des. 850,537.
